UNITED STATES PATENT OFFICE.

FREDERICK L. TAIT, OF VANCOUVER, BRITISH COLUMBIA, CANADA.

POCKET BRUSH AND COMB.

1,413,810.

Specification of Letters Patent. Patented Apr. 25, 1922.

Application filed September 8, 1921. Serial No. 499,189.

To all whom it may concern:

Be it known that I, FREDERICK L. TAIT, a citizen of the Dominion of Canada, residing at Vancouver, in the Province of British Columbia, Canada, have invented certain new and useful Improvements in Pocket Brushes and Combs, of which the following is a specification.

This invention relates to a pocket brush and comb, the comb being slidably mounted in the medial line of the brush to fit within the same when not required, and susceptible of being withdrawn that either may be used, thus forming a simple, compact and convenient combination, either for pocket or dressing case.

The invention is particularly described in the following specification, reference being made to the drawings by which it is accompanied, in which:

Fig. 1 is a side elevation of the brush and comb as closed when out of use, the dot and dash lines indicating the extension of the comb from the brush when either part is to be used.

Fig. 2 is an end view of Fig. 1, and

Fig. 3 is a modified form showing the application of two combs to a wider brush.

In these drawings 2 represents the back or body of the brush having preferably one row of bristles 3 on each side of a medial channel 4 which extends lengthwise of the brush from adjacent one end to the other open end.

Through the open end of this channel 4 the back 5 of the comb is endwise slidable, being retained on pins 6 secured in the back of the brush through a lengthwise slot 7 in the back 5 of the comb.

The teeth 8 of the comb are preferably slightly within the depth of the bristles 3 and when closed to its limit in the brush the end of the comb projects slightly and is provided with a nail engagement 9 by which the comb may be withdrawn for use.

Figure 3 shows a modified form wherein the brush has two or more rows of bristles 3 on each side of the medial channel 4 and

two combs 5 are independently slidable, side by side, which combs may have fine and coarse teeth respectively.

The brush and comb may not only be used separately but together, as the teeth of the comb will separate and arrange the hair locks while the brush will smooth it down.

I am aware that combs and brushes have heretofore been associated in slidable relationship, but not in the same, simple, compact and effective manner herein set forth.

Having now particularly described my invention, I hereby declare that what I claim as new and desire to be protected in by Letters Patent, is:

1. A pocket brush and comb, comprising the combination with a brush having a channel medially disposed between the bristles in the underside of its back, of a comb the back of which has a lengthwise slot through it and is endwise slidable in the medial channel of the brush and pins across the open end of the channel and through the slot of the comb.

2. A pocket brush and comb, comprising the combination with a brush having a channel in the medial line extending from a short distance from one end through the other end, a comb endwise slidable in the channel and projecting slightly beyond the open end of the same when at the inner limit of its movement, said comb having a lengthwise slot in its back, and pins through the body of the brush adjacent the open end of the channel and through the slot in the back of the comb.

3. A pocket brush and comb comprising the combination with a brush having a channel disposed in the under side of its back, of a comb, the back of which is endwise slidable in said channel and means for limiting the endwise sliding movement of said comb, whereby said comb may project partly beyond the end of the brush separate from the bristles thereof, substantially as shown and described.

In testimony whereof I affix my signature.

FREDERICK L. TAIT.
